BOAT

John Lindsay, 16 Harbor St., Manchester, Mass.

Filed Mar. 3, 1965, Ser. No. 84,070

Term of patent 14 years

(Cl. D71—1)

FIG.1

FIG. 1 is a side elevation of my new boat design; FIG. 2 is a top plan view of my new design; and FIG. 3 is a rear perspective view of the boat shown in FIG. 1.

The dominant feature of the design is shown in full lines in the drawings.

I claim:

The ornamental design for a boat, as shown and described.
